UNITED STATES PATENT OFFICE.

HERMANN RÖTHLISBERGER, OF ZURICH, SWITZERLAND.

CLAMPING DEVICE.

Application filed August 11, 1924. Serial No. 731,534.

To all whom it may concern:

Be it known that I, HERMANN RÖTHLISBERGER, a citizen of Switzerland, residing at Zurich 6, Switzerland, have invented certain new and useful Improvements in Clamping Devices, of which the following is a specification.

My invention relates to an improved clamping device for any piece of work to be subjected to the treatment of a tool or to be kept down and retained in a clamped position. The said improvement consists in providing a clamp which allows to the working tool a variety of positions with relation to the piece of work. Such variety is obtained by two co-operating clamping means which permit the adjustment of the clamping means in an angular position with relation to the piece of work to be fixed. One of said two means consists of an upright spindle turning on a ball socket and, thereby, being adapted to be turned to every side, while the other means consists of a flexible joint interposed between the said rotatable spindle and the clamping jaw proper, said joint adapted to be taken asunder and containing a pair of ratchet-wheels, which are made to engage and to disengage by the aid of a spring interposed. In the accompanying drawings I have illustrated my invention which I am going to describe in the following:

Fig. 1 is a side elevation of the clamping device, partly shown in section.

Fig. 2 is a plan-view of Fig. 1.

Fig. 3 is a side-elevation of the spring-actuated ratchet.

Fig. 4 is a plan of a part of the clamping arm, and

Fig. 5 is a side-elevation of the lower part of the ratchet with the spring surrounding it.

The clamping-device of this invention is composed of a few parts which, in their way of working, are different from other known clamping devices, in that, first, the upright spindle α , supporting one end of the clamping arm f , is turning on a foot formed by a ball d , and, thereby, is adapted to take any oblique position to any side. On the screw-thread surrounding said spindle, a nut c is arranged to slide up and down, said nut being made integral or rigidly fixed to a short arm s , forming a flexible joint between the clamping arm f and the said spindle α .

As will be seen from Fig. 1, the spindle

α may be forced into an oblique direction indicated by a dotted line, and the said arm s , owing to the nut c engaging the screw-thread, will be forced to adapt itself to the corresponding angular position.

The mechanism for obtaining such flexible combination, on which resides the usefulness of this invention, will be further explained by the working method of the whole mechanism.

The clamping-device, being secured to the bed-plate of any work-bench, exerts its clamping pressure on the piece of work q to be clamped by means of a claw or claws p , p , which are adjustable in height by means of a threaded spindle o , slideable within the longitudinal slot n of the clamping arm f , the foot of said spindle o , sliding in a known manner within a groove of the bed-plate; a nut exerting a downward pressure on the said arm f on the claw or claws p , p , firmly pressing them on the piece to be clamped. The end of the arm f opposite to the claw p is connected by arm s to the nut c adapted to move up and down on the thread of the spindle α . The said spindle α is seated with a ball d within a spherical seat of a bearing e within which it may turn to every side, as far as the length of the arm s of the joint and a longitudinal shifting motion of the clamping arm f , will allow, as indicated by dotted lines in Fig. 1. By such displacement the space of the tool working upon the piece of work is materially enlarged and it may be changed to every side.

The joint provided within the clamping arm f which permits of adjusting the angular position of the clamping-device and its fixing the same in any position, simultaneously allowing of taking asunder its parts and for replacing the same into the position of use, in a most simple manner, is shown in detail by Figs. 2, 3, 4 and 5. On the end of the arm f remote from the clamping jaws p , rigidly connected to the nut c by the arm s , a bolt i is passed within a fork-shaped recess of said arm s . Said fork encloses the two ratchet-disks g and g^1 , provided with ratchet-teeth h , h^1 , the former one g of which is rigidly connected with the clamping arm f , while the other disk g^1 is prevented from turning by a square portion m of the bolt i . By the tension of a spring l surrounding the lower disc g^1 , the two discs g , g^1 are pressed against each other, this

making their teeth engage each other. By adjusting the arrangement in the manner indicated by dash-and-dotted lines in Fig. 1, the disc *g* of the clamping arm *f* will be turned around the bolt *i*, while the disc *g'* is being pressed back till the required position has been reached. For opening the joint, the thumb-screw *h* is loosened and the bolt *i* may be withdrawn.

10 I claim as my invention:

1. In a device for adjustably clamping, the combination with a supporting spindle, of a ball-joint, a spherical seat supporting said spindle in a manner to turn on said ball in any direction, a clamping arm connected to said spindle by a nut turning round a thread of said spindle, and a joint interposed in said clamping arm for adapting itself and the said clamping arm to the flexible motion of the said spindle.

2. In a device for adjustably clamping, the combination with a supporting spindle,

of a ball-joint, a spherical seat for supporting said spindle, a clamping arm connected to said spindle by a nut, a joint interposed in said clamping arm, said joint comprising a ratchet-wheel, and a spring for tightening and releasing said joint. 25

3. In a device for adjustably clamping, the combination with a supporting spindle, of a ball-joint, a spherical seat for supporting said spindle, a clamping arm connected to said spindle by a nut, a joint interposed in said clamping arm, said joint comprising a ratchet-wheel and a spring for tightening 30 and releasing said joint, and a thumb-screw for opening said joint.

In testimony whereof I have affixed my signature in presence of two witnesses.

HERMANN RÖTHLISBERGER.
